UNITED STATES PATENT OFFICE.

FRANZ RAMMELMEYER, OF HEIDELBERG, GERMANY.

GAME.

Application filed August 7, 1924. Serial No. 730,681.

To all whom it may concern:

Be it known that I, FRANZ RAMMELMEYER, a German citizen, and residing at Heidelberg, Germany, have invented certain new and useful Improvements in a Game, of which the following is a specification.

This invention relates to an apparatus for playing a strategical game of the kind wherein each player is provided with a number of roof-shaped or other figures the values of which are hidden from the opponent and which are moved over a board divided into square or other shaped spaces.

On the accompanying drawing: Fig. 1 represents the playing-board, while Figs. 2 and 3 show a roof-shape for the figures in a side view and front view respectively.

The playing-board is similar to a checkers board and divided into a large number of squares, circles, or other regular sections, preferably of alternately different or of uniform color, and it is separated in the middle by a neutral zone 3 into two hostile fields 1 and 2, which are connected by 4 bridges 4 across the neutral zone. An invasion into the hostile field can take place only across the 4 connecting bridges. The game may also be played without the bridges, by making use of the squares in the neutral zone. Thereby, the game develops more quickly though it is more difficult to play, because then the attack can take place all along the front of the adversary.

The figures 5 are roof-shaped and differ from each other by having detachable distinguishing badges thereon taken from army or navy or aeronautic ranks or from the zoology, or with consecutive numerals, names of illustrious persons, or the like, said badges being removably located by means

of clips 6 on one side of the figures only, said latter side always facing the player during the play.

In the improved strategical game, neither party is allowed to find out the value of his adversary's figures. For this reason, 3 persons take part in the game, of whom one is the umpire. Only the umpire is permitted to look at the rank of the figures of both parties during the game. The office of the umpire is, thus, at least as interesting as the part of the two players. This is what makes the game exciting and gives it an ever fresh interest, namely that the adversary remains ignorant of the character of the different figures, even when the umpire has to remove lost figures from the board.

What I claim, is:

1. A strategical game apparatus comprising, like a checkers game, a playing-board and two sets of figures and to be played by two parties and one umpire, said figures being roof-shaped, and detachable distinguishing badges removably located on one side of said figures only, said latter side always facing the player during the play, so that neither party is allowed to find out the character of his adversary's figures, this being left to an umpire only.

2. Apparatus as specified in claim 1: in which said playing-board is separated in the middle by a neutral zone into two hostile fields connected by 4 bridges across the neutral zone.

In testimony whereof I have hereunto set my hand in the presence of two subscribing witnesses.

FRANZ RAMMELMEYER.
